TIRE

Michael N. Young, Tucson, Ariz., assignor to The
Goodyear Tire & Rubber Company

Filed Oct. 15, 1973, Ser. No. 406,528

Term of patent 14 years

Int. Cl. D12—15

U.S. Cl. D12—143

FIG. 1 is a perspective view of a tire showing my new design, it being understood that the design is repeated throughout the circumference of the tire as shown schematically by solid lines, the opposite side being substantially the same as that shown.

FIG. 2 is a cross-sectional view taken on line 2—2 of FIG. 1.

I claim:

The ornamental design for a tire, substantially as shown and described.
